UNITED STATES PATENT OFFICE.

WALTER D. BONNER, OF SALT LAKE CITY, UTAH.

PROCESS OF PURIFYING BEET-MOLASSES.

1,362,078.

Specification of Letters Patent. Patented Dec. 14, 1920.

No Drawing.

Application filed October 12, 1917. Serial No. 196,320.

To all whom it may concern:

Be it known that I, WALTER D. BONNER, a citizen of the United States, residing at Salt Lake City, in the county of Salt Lake 5 and State of Utah, have invented certain new and useful Improvements in Processes of Purifying Beet-Molasses, of which the following is a specification.

This invention is a process whereby the 10 refuse molasses of beet-sugar factories may be converted into a wholesome, edible product. Potassium salts are recovered as a by-product of the operation.

Beet-molasses, a by-product of beet-sugar 15 manufacture, contains a relatively high percentage of potassium salts, which impart to it a highly disagreeable taste. It is also characterized by a strong and unpleasant odor. The object of this invention is to 20 provide a simple and economical method, preferably cyclical in character, whereby these objections may be overcome.

I prefer to proceed substantially as follows, it being however understood that the 25 invention is not restricted to particular proportions of reagents or additions, or to the particular manipulations specified herein in connection with the description of a typical operation.

30 Five hundred pounds of beet-molasses is diluted with about three hundred pounds of hot water, and the mixture is stirred to form a homogeneous solution. Either more or less water may be added, it being essential 35 only that the solution should be sufficiently diluted to permit an easy separation of the precipitate subsequently produced. Practically, the amount of water added should not in the case of ordinary beet-molasses 40 be less than one-half of the weight of the molasses.

Tartaric acid, either solid or previously 45 dissolved in water, is now added in proportion to precipitate the bulk of the potassium compounds in the form of the difficultly soluble acid potassium tartrate, the liquid, which was initially alkaline, being at the same time rendered slightly acid. Since 50 there is some variation in the percentage of potassium salts in different samples of molasses, the quantity of tartaric acid required will be subject to some variation, and must

be determined for each grade of molasses. As a general rule the quantity required will be in the neighborhood of thirty-four 55 pounds of tartaric acid for each five hundred pounds of the original molasses.

The mixture is now thoroughly stirred, by paddles, air-blast or otherwise; and is then allowed to stand until cold. During 60 the cooling the acid potassium tartrate settles out from the solution, and the cold syrup may be decanted through any appropriate filtering or separating device, as a filter-press, centrifuge or the like. The 65 purified syrup is then evaporated, preferably *in vacuo*, to about the consistence of the original molasses or as far as may be desired. During this evaporation of the slightly acid liquid, volatile bodies to which 70 the molasses owes its strong and unpleasant odor are expelled, leaving the product (syrup) pleasant, wholesome and appetizing.

The precipitated acid potassium tartrate 75 may now be treated with the appropriate quantity of sulfuric acid to set free the tartaric acid, the potassium being recovered in the course of this operation in marketable condition as the sulfate. The tartaric acid 80 thus recovered is available for re-use in the purification process, which is thereby, in its preferred embodiment, rendered cyclical in character. This recovery of tartaric acid 85 and potassium sulfate from the acid tartrate precipitate may be carried out in accordance with the well-known methods.

I claim:—

1. Process of purifying beet-molasses, comprising suitably diluting the molasses, 90 adding thereto sufficient tartaric acid to precipitate the bulk of the potassium as acid potassium tartrate, separating the molasses from the precipitate, and completing the purification by evaporation.

2. Process of purifying beet-molasses, comprising suitably diluting the molasses, slightly acidifying with tartaric acid, separating the resulting precipitate from the partially purified syrup, and completing the 100 purification by evaporating the latter *in vacuo*.

3. A process of purifying beet-molasses, comprising suitably diluting the molasses,

precipitating potassium compounds therefrom by tartaric acid, separating the acid potassium tartrate from the molasses, recovering tartaric acid from the tartrate precipitate, and completing the purification of the molasses by evaporation.

4. In a process of purifying beet-molasses,

the steps which consist in eliminating potassium compounds therefrom by precipitation as acid potassium tartrate, and completing 10 the purification of the molasses by evaporating the slightly acid solution.

In testimony whereof I affix my signature.
WALTER D. BONNER.
